UNITED STATES PATENT OFFICE.

JAMES H. DOUSMAN, OF KANSAS CITY, MISSOURI.

HANGER.

No. 820,771.

Specification of Letters Patent.

Patented May 15, 1906.

Application filed July 6, 1905. Serial No. 268,498.

To all whom it may concern:

Be it known that I, JAMES H. DOUSMAN, a citizen of the United States, residing at Kansas City, in the county of Jackson and State 5 of Missouri, have invented certain new and useful Improvements in Hangers, of which the following is a specification.

My invention relates to hangers for supporting false work for cement flooring, ceiling, and other suspended work; and my object is to produce a cheap hanger of this character which performs its work efficiently and reliably.

A further object is to produce a hanger of this character of such construction that its more expensive portion can be easily dislodged, after the cement or concrete flooring is "set," for future use.

To these ends the invention consists in certain novel and peculiar features of construction and organization, as hereinafter described and claimed, and in order that it may be fully understood reference is to be had to the accompanying drawings, in which—

Figure 1 is a vertical cross-section taken on the line I I of Fig. 2. Fig. 2 is a horizontal section taken on the line II II of Fig. 1 with the cement flooring omitted. Fig. 3 is a detail perspective view of a modified construction of a hanger with its parts in operative relation. Fig. 4 is a plan view of the same with the parts in the position they are caused to assume for the purpose of dislodging or removing the rod members; said construction being modified in a respect hereinafter referred to.

In the said drawings, 1 indicates one of the customary I-beams or its equivalent used in the construction of floors and ceilings.

2 indicates headed rods arranged vertically at opposite sides of the base-flanges of the I-beam with their non-headed ends projecting above said base-flanges, said non-headed ends being provided with threads 3 in Fig. 1 and with one or more outwardly-projecting lugs 4 in Figs. 3 and 4.

5 indicates detachable heads for the non-headed ends of the rods, said heads in Figs. 1 and 2 being in the form of eccentrically-pierced nuts, while in Fig. 3 they are in the form of eccentrically-pierced plates provided with one or more offsetting passages 6, through which lugs 4 may freely pass. The detachable heads in each case inward of the rods rest upon the base-flanges of the I-beams, and in order to reduce the leverage on

said rods said overlying portions of said detachable heads are beveled at their under sides at 7 to correspond with, and therefore rest squarely upon, the upper inclined sides of 60 said base-flanges, as shown clearly in Fig. 1. In this connection it should be stated that while said detachable heads are preferably pierced eccentrically, so as to obtain a longer bearing on the flanges of the I-beam, it is not 65 absolutely essential that heads of such construction be employed, as an ordinary nut of sufficient size may be utilized for said head.

8 indicates cross-bars fitting upon rods 2 and supported upon the permanent heads 70 thereof, and 9 indicates longitudinal planks or timbers resting upon said cross-bars, it being understood in this connection that there will be a series of hangers depending from each I-beam in order to form a proper support for 75 the longitudinally-extending planks or timbers, and it will also be understood that said cross-bars and planks or timbers are preferably secured in position before the heads are secured upon the upper ends of the rods to 80 support them in position, the workman reaching in from opposite sides of the planking 9 to secure said detachable heads in operative position. After the planking is thus suspended from the beam the side planking 85 10 and uprights 11 are secured in place, the latter serving to support the side planking 10 in place and also to support the planking 12, which underlies and forms a base for that portion of the cement flooring extending 90 from beam to beam, it being understood, of course, that the opposite ends of the floor-planking 12 rest upon the uprights 11 of contiguous beams. To this false work *per se* no claim is made, because it is of common and 95 well-known type, and it is only claimed in combination with this character of hanger. After the false work is secured the cement or concrete is deposited to about the level indicated in Fig. 1, that portion occupying 100 the space between side planking 10 and floor-planking 9 forming depending ribs 13 in line with and below each I-beam, as usual, while the portion 14 forms the major part of the floor between the beams. It is to be understood that the rods receive a coating in any suitable manner of heavy lubricating-oil, so as to prevent the cement adhering to them so tightly as to prevent them turning. After the cement has set the workmen unscrew the rods 2 sufficiently to permit the side planking and uprights to be removed and 110

then unscrew said rods until they are wholly withdrawn from the detachable heads, which of course remain embedded in the cement or concrete, the cross-bars 8 and flooring 9 being removed from position with the rods. The above remarks apply to the construction shown in Figs. 1 and 2.

With the construction shown in Fig. 4 the rods are turned until lugs 4 register with passages 6 and are then withdrawn from the detachable heads, the false work being removed in the usual manner. If it is desired, with the type of hanger shown in Figs. 3 and 4, to permit of the removal of the side planking, uprights, and flooring 12 before the rods are totally withdrawn, the upper sides of the detachable heads may be provided with the inclined recesses 15, as shown in Fig. 4, said recesses curving concentrically of the openings 20 and inclining downward toward the passages 6, so that the rods may be turned and permit of the removal of said side planking, uprights, and flooring 12 before the rods are totally withdrawn.

From the above description it will be apparent that I have produced apparatus of the character described possessing the desirable features enumerated and which ob-

viously may be modified in minor particulars without departing from the principle of construction involved.

Having thus described the invention, what I claim as new, and desire to secure by Letters Patent, is—

In false work for concrete building construction, the combination with a beam forming a part of the permanent structure and having lateral flanges at its lower end, of plates or heads supported by and projecting slightly beyond said flanges and provided with openings near their outer ends, and removable supporting rods detachably engaged in said openings, supported by said plates and depending therefrom on opposite sides of the beam, said rods being provided with fixed heads at their lower ends to support staging between which and the beam concrete may be placed, and the plates or heads being permanently surrounded by and embedded in the concrete.

In testimony whereof I affix my signature in the presence of two witnesses.

JAMES H. DOUSMAN.
